RAINCOAT SLEEVE

Benjamin B. Spatz, New York, N. Y.

Application August 30, 1938, Serial No. 227,447

3 Claims. (Cl. 2-269)

This invention relates to a cuff and sleeve construction for a raincoat. More particularly, this invention relates to a raincoat sleeve which is through its cuff adapted for adjustment into two 5 lengths.

While it is admittedly old to have cuffs for garments whereby the sleeves may be adjusted to two lengths, such cuffs are usually formed so that when adjusted to one of the two lengths, they 10 present an unsightly appearance, and give the impression that they are adjusted to this length simply as an expedient, and that the said adjustment is merely a "makeshift". The cuff and sleeve of my invention present a finished and 15 slightly appearance in either adjustment.

Also, such adjusting of the sleeve and cuff as has been developed by the prior art is not generally adapted to give complete coverage of the wrist when the sleeve is adjusted to its greatest 20 length, since the cuff will not in this position form a complete circle. In a raincoat, it is quite necessary that in either adjustment of the sleeve, a complete circle be formed so that the wrist may be fully protected against the weather. As already indicated, it is also important in a raincoat 25 of the better quality that the sleeve in either adjustment have a finished appearance. My invention provides the features discussed, also other advantages that will be pointed out below. 30 For a description of my invention, I shall now refer to the drawing wherein Fig. 1 is a perspective view showing my sleeve with the cuff adjusted for a short sleeve length. Fig. 2 is a similar view showing my sleeve with the cuff adjusted for a long length sleeve. Figs. 3 and 4 are respectively figures taken along lines 3-3 and 4-4 of Fig. 1.

Referring now more particularly to the drawing, my sleeve is designated by reference numeral 10, and has secured thereto on approximately the line 11, a cuff 12. The securing may be by sewing or by cementing, or both. I shall describe it here as sewed, for convenience. The cuff 12 may be considered as made up of outside and inside 45 halves terminating respectively in flaring ends 13 and 14, the flaring end 13 being equipped with an angular button hole 15, while the flaring end 14 is equipped with a button 16.

With the cuff adjusted for a long length sleeve, as in Fig. 2, the flaring ends 13 and 14 will overlap substantially so as to present a complete circle for encircling the wrist of the wearer. The flaring end 13 has purposely been shown spaced from end 14 to better illustrate the parts. Actually, flaring end 13 will lie closely to end 14. The

button 16 will extend through the button hole 15 so as to be present on the outside of the sleeve, and to present a slight appearance and also a finished appearance, so that the sleeve and cuff will appear to have been designed for use as illustrated in the figure, and will not appear to have been adjusted to the position of Fig. 2 simply for expediency.

The angular relation of the button hole 15 to the cuff is important in the particular assembly 19 because the button hole through its said angular relation prevents the easy movement of the button 16 outwardly thereof, and will hold the cuff in its assembled position of Fig. 2.

Fig. 1 shows the cuff portions folded upwardly adjacent the line on which the cuff is sewed to the cuff 10. In this relation of the parts, the cuff will extend upwardly from a complete circle formed by the lower edge of the sleeve 10, as is shown in section in Fig. 4. The sleeve 10 will be gathered somewhat by the securing together of the flared ends 13 and 14 through the passing of the button 16 through the button hole 15. In this position of the cuff, a finished appearance will be presented, just as in the position of Fig. 2. The button 16 will appear on the outside of the sleeve, just as in Fig. 2. The angular button hole 15 will function just as it does in Fig. 2, and as was indicated previously, a complete circle will be formed by the cuff and sleeve and will protect the wrist of the wearer.

In Fig. 3, the cuff 12 is shown in section as formed of two thicknesses of material, its relation to the sleeve 10 being also illustrated.

The construction of my sleeve will now appear quite clear, and the advantages particularly pointed out at the beginning of this specification will now probably be better appreciated.

I now claim:

1. In a garment of the class described, a sleeve having a cuff portion sewed thereto along a predetermined line, the said cuff portion having flaring ends substantially aligned when said sleeve and cuff are folded flat and said cuff is fully extended, said cuff when flat having, in effect, an inside half and an outside half, the inside half of the cuff having a button sewed thereto in its flared end region and facing towards the garment, the other half of the cuff having a button hole in its flared end region, the button of the cuff being insertible through said button hole to form a barrel-type cuff and with said flaring ends overlapping substantially, and with the button then facing away from the garment, the said cuff being foldable upwards along the predetermined ..

line on which it is secured to the sleeve to form a French type cuff, this bringing the flaring ends into substantial alignment but with the button facing away from the garment but covered by the other half of the cuff, the said button being then insertible through said button hole to complete the cuff and with the button outside.

2. In a garment of the class described, a sleeve having a cuff portion sewed thereto along a predetermined line, the said cuff portion having flaring ends substantially aligned when said sleeve and cuff are folded flat and said cuff is fully extended, said cuff when flat having, in effect, an inside half and an outside half, the inside half of the cuff having a button sewed thereto in its flared end region facing towards the garment, the outside half of the cuff having a button hole in its flared end region, the button of the cuff being insertible through said button hole to form a barrel-type cuff through the cooperation of said flaring ends, and with the button facing away from the garment, the said cuff being foldable upwards substantially along the predetermined line on which it is secured to the sleeve to form a French-type cuff, this bringing the flaring ends into substantial alignment but with the button facing away from the garment but covered by the other half of the cuff, the said button being then insertible through said button hole to complete the cuff and with the button outside, the said cuff and its

flaring ends maintaining the sleeve somewhat gathered.

3. In a garment of the class described, a sleeve having a cuff portion sewed thereto along a predetermined line, the said cuff portion having flaring ends substantially aligned when said sleeve and cuff are folded flat and said cuff is fully extended, said cuff when flat having, in effect, an inside half and an outside half, the inside half of the cuff having a button sewed thereto in its flared end region facing towards the garment, the other half of the cuff having a button hole in its flared end region, the button of the cuff being insertible through said button hole to form a barrel-type cuff through the cooperation of said flaring ends, the said button hole being at an angle of approximately 45° to the parallel upper and lower edges of said cuff whereby to better hold said button in inserted relation thereto, and with the button facing away from the garment, the said cuff being foldable upwards along the predetermined line on which it is secured to the sleeve to form a French-type cuff, this bringing the flaring ends into substantial alignment but with the button facing away from the garment but covered by the other half of the cuff, the said button being then insertible through said button hole to complete the cuff and with the button outside.
